(57) **CLAIM**

The ornamental design for a cane with guided height adjustment lines, as shown and described.

DESCRIPTION

FIG. 1—A perspective view of the claimed design, showing the overall appearance thereof.

FIG. 2—A bottom perspective view of the claimed design, showing the guided height adjustment lines and the base thereof.

FIG. 3—A right side view of the claimed design, illustrating the height adjustment lines in profile.

FIG. 4—A right side view of the claimed design shown in an environment, with unclaimed environmental features thereof indicated by broken lines.

FIG. 5—A front view of the claimed design.

FIG. 6—A front view of the claimed design shown in an environment, with unclaimed environmental features thereof indicated by broken lines.

FIG. 7—A left side view of the claimed design.

FIG. 8—A left side view of the claimed design shown in an environment, with unclaimed environmental features thereof indicated by broken lines.

FIG. 9—A rear view of the claimed design.

FIG. 10—A rear view of the claimed design shown in an environment, with unclaimed environmental features thereof indicated by broken lines.

FIG. 11—A top view of the claimed design.

FIG. 12—A top view of the claimed design shown in an environment, with unclaimed environmental features thereof indicated by broken lines.

FIG. 13—A bottom view of the claimed design; and,

FIG. 14—A bottom view of the claimed design shown in an environment, with unclaimed environmental features thereof indicated by broken lines.

The broken lines are for environmental purpose only and form no part of the claimed design.

1 Claim, 7 Drawing Sheets
